UNITED STATES PATENT OFFICE.

FRANK P. TENNEY, OF NEW YORK, N. Y., ASSIGNOR TO UNITED BUTTON COMPANY, A CORPORATION OF NEW YORK.

BUCKLE.

932,596.

Specification of Letters Patent. Patented Aug. 31, 1909.

Application filed February 15, 1908. Serial No. 416,010.

To all whom it may concern:

Be it known that I, FRANK P. TENNEY, a citizen of the United States of America, and a resident of the borough of Manhattan, city of New York, county of New York, and State of New York, have invented certain new and useful Improvements in Buckles, of which the following is a specification.

The present invention relates generally to 10 buckles and is more particularly designed as an improvement on the construction shown in Letters Patent No. 710,641 of October 7, 1902.

The main object of the invention is the 15 production of a buckle having no sharp prongs, the cloth or other material being held by opposed blunt prongs on the frame and grip without piercing the cloth.

In the patent above referred to these 20 opposed prongs on the frame and grip were located in alinement with each other, and without overlapping. It has been found that if the cloth or other material is heavy it will not be possible to close the grip properly 25 owing to the short distance between the opposed prongs.

The characteristic feature of the present 30 invention resides in staggering these prongs and in having a greater number of prongs on one side than on the other. The arrangement is preferably such that for every prong on one side there are two prongs on the other side so that the cloth or other material is gripped at three points as it were in a number 35 of places. The fact that the prongs are staggered allows ample room for the cloth and the fact that the prongs are more numerous on one side than on the other insures a firm hold on the material.

Another feature of the invention resides in 40 the fact that when the grip is closed the prongs carried thereby are in a plane different from that of the prongs on the frame, whereby a heavy thickness of material can 45 be accommodated.

Another feature of value resides in bending 50 up the sides of the forward portion of the sheet metal frame to form bearings for the grip and in providing the frame with an extension at an angle to the main portion of the frame so as to produce a holding guide for the end of the strap or material held by the prongs of the frame and grip.

In the accompanying drawing the invention 55 is embodied in a concrete and preferred

form but such changes of construction as come within the scope of the appended claims may of course be made without departing from the legitimate and intended scope of the invention.

In the said drawings: Figure 1 is a plan view of a buckle embodying the invention with the grip in its closed position. Fig. 2 is a sectional view on the line 2—2 of Fig. 1. Fig. 3 is a plan view similar to Fig. 1 but 65 partly broken away showing how the material is held by the prongs. Fig. 4 is a section on the line 4—4 of Fig. 3 with the grip in its open position. Fig. 5 is a sectional view on the irregular line 5—5 of Fig. 3 with the grip 70 in its closed position.

Similar characters of reference indicate corresponding parts in the different views.

1 indicates a frame, which may be of any 75 convenient configuration, provided with the inwardly extending blunt prongs 2. Mounted on the pivots 3 is the grip 4 provided with a plurality of prongs 5—5, 6—6 and 7—7.

In the manufacture of the buckle, the frame is preferably stamped out of a flat 80 blank, and the sides at the forward portion of the frame are then turned up at right angles to form bearings for the pivots of the grip, this causing a twist 11, in the rearward portion of the frame.

85 8 indicates a stop for limiting the closing movement of the grip, and 9 indicates a swelling on the frame which is intended to produce friction when the grip is being moved into its closed position. The rearward end of the frame is provided with an extension 10 which forms a holding guide for the end of the strap held by the frame and grip. This extension is formed integral with the main portion of the frame, the stock being twisted at 11 and the extension being bent at an angle to the main portion of the frame so as to facilitate the insertion of the end of the strap.

90 95 It will be seen from Fig. 2 that the prongs on the grip are in a plane different from the prongs on the frame when the grip is in its closed position.

When the material is inserted into the 100 buckle and the grip is closed the blunt prongs 105 on the frame and grip will hold the material as indicated in Fig. 3. As there shown each prong on the frame co-operates with two prongs as 5—5 for instance on the grip so as to hold or pinch the material at three points 110

in a number of places. At the same time owing to the staggered position of the opposed prongs and to the fact that the space intervening between the prongs of the frame is very great, ample room is afforded for the material without unduly wrinkling the same.

I claim:

1. A buckle comprising a frame and a grip, the latter swinging within the frame, and a plurality of prongs divided into two opposed sets on the frame and grip, but located in different planes when the grip is in its closed position, and the prongs of the two sets being staggered with relation to each other the prongs of the two sets being so arranged that between any two adjacent prongs of one set will be a pair of prongs of the opposite set.
2. A buckle comprising a frame and a grip pivoted in the frame, a plurality of opposed prongs on the frame and grip, the prongs of one set being more widely spaced and of fewer number than the prongs of the other set, and the prongs of the two sets being arranged in staggered relation.
3. A buckle comprising a frame, and a grip pivoted in the frame, a plurality of opposed prongs on the frame and grip, the prongs of the opposing sets being arranged

so that two prongs of one set will lie between two adjacent prongs of the opposite set.

4. A buckle comprising a frame, and a grip pivoted in the frame, a plurality of opposed prongs on the frame and grip, the prongs of the two sets being arranged in staggered relation, there being twice as many prongs on the grip as on the frame and two prongs of the grip lying between each two adjacent prongs of the frame and a strap holding guide extending from the rearward portion of the frame.

5. A buckle comprising a frame and a grip pivoted in the frame, a plurality of opposed prongs on the frame and grip, the prongs of the two sets being arranged in staggered relation, there being more prongs on the grip than on the frame and arranged so that two prongs of the grip will lie between each two adjacent prongs of the frame.

Signed at New York city, this 30 day of January 1908.

FRANK P. TENNEY.
